Inventor:
Hugh M. Stephenson,
by *Hugh M. Stephenson*,
His Attorney.

UNITED STATES PATENT OFFICE.

HUGH M. STEPHENSON, OF FORT WAYNE, INDIANA, ASSIGNOR TO GENERAL ELECTRIC COMPANY, A CORPORATION OF NEW YORK.

SEWING-MACHINE TAKE-UP.

Application filed July 13, 1927. Serial No. 205,480.

My invention relates to sewing machines and its object is to provide an improved and simplified oscillating lever take-up mechanism for varying the length of the thread taken up in proportion to the thickness of the material being sewn.

My invention will be more fully set forth in the following description referring to the accompanying drawing and the features of novelty thereof will be pointed out with particularity in the claims annexed to and forming a part of this specification.

In the drawing, Fig. 1 is a side elevation partly broken away of a sewing machine embodying my improved take-up; Fig. 2 is a section of the arm of the machine on the line 2—2 of Fig. 3; Fig. 3 is an end elevation of the arm of the machine with the cover plate partly broken away, and Fig. 4 is a perspective view of the take-up arm and related parts.

Referring to the drawing, the sewing machine in connection with which I have illustrated my invention comprises a bed-plate 10 having an overhanging arm 11 extending therefrom for supporting the needle bar 12, presser-foot 13^a and take-up 14. A needle 12^a carried by the needle bar 12 and the presser-foot 13^a carried by the presser-bar 13 cooperate with a feed dog 15 and a suitable loop-taker arranged below the bed-plate 10 to form stitches in the usual manner. During the operation of the machine thread is supplied to the needle 12^a through the tensioning device 16, eyelet 14^a of the take-up lever, upper thread guide 17 and lower thread guide 18, so that the downward movement of the take-up lever 14 forms an enlarged thread loop between the tensioning device 16, eyelet 14^a and thread guide 17. The proper timing of the movement of the needle bar 12 and take-up 14 relative to the feed-dog 15 and the loop-taker is insured by a mechanical connection between these parts including the horizontal shaft 19 supported in the arm 11 which is also connected to a suitable driving means (not shown). The needle bar 12 is actuated by a crank 20 and connecting rod 21 which are supported on the end of a cam 22 connected to the shaft 19. In accordance with my invention the take-up lever 14 is pivotally mounted at 23 on a block 24 which is slidably supported in a slot 25 formed in

the side wall of the arm 11. The take-up lever is oscillated about its pivotal support 23 by a roller 26 thereon which engages the cam 22 which is actuated by the horizontal shaft 19. It will be noted that the block 24 can be shifted in the slot 25 to vary the position of the pivotal support 23 relative to the cam 22 and to vary correspondingly the distance that the take-up lever 14 moves below the upper thread guide 17, which controls the amount of thread taken up by the movement of the take-up lever and which advances the thread sufficiently to form the succeeding stitch. This variation in the length of the thread taken up by the movement of the take-up lever 14 occurs because the size of the loop formed between the tensioning device 16, take-up lever 14 and thread guide 17 depends upon the distance which the take-up lever 14 moves below the upper thread guide 17 and the tensioning device 16. The length of thread taken up and advanced by the movement of the take-up lever 14 is not affected by the variations of the distance between the eyelet 14^a and the thread guide 17 when the take-up lever is in its uppermost position, because the slight amount of slack thread which is provided in the loop when the take-up lever is nearest the thread guide 17 is sufficient to prevent the take-up lever from exactly controlling the thread in this position.

It is well understood in the art that it is desirable to increase the amount of thread taken up and advanced by the take-up mechanism as the thickness of the material being sewn increases. This is accomplished according to my invention by providing the presser-bar 13 with a cam 27 extending through a slot 28^a in a link 29 which is connected to the pivotal take-up lever support 23 and is arranged to move the same so as to increase the length of thread taken up and advanced in proportion to the thickness of the material under the presser-foot. In order to prevent the cam 27 moving the link 29 vertically the latter is arranged to slidably engage a guide 30 formed on the side wall of the arm 11. The cam 27 is provided with a straight portion 27^a which conforms to the slot 28^a but does not shift the position of the link 29 so that it will not interfere with the raising of the presser-bar

13 by the presser-foot release lever 13^b when the presser-foot is raised to remove the material from the machine.

In the operation of the sewing machine 5 described the rotatable shaft 19 actuates the take-up lever 14 which is oscillated about its pivotal support 23 by the cam 22 and periodically takes up the thread by forming an enlarged loop between the thread tensioning device 16 and the thread guide 17, advancing the thread length at the extreme lower stroke position sufficiently to form the succeeding stitch after completing a stitch, in this way cooperating with the remainder 10 of the stitch forming mechanism to form stitches in the usual manner. The feeding of material under the presser-foot 13^a by the feed-dog 15 raises the presser-bar 13 against the presser-bar spring 13^c and causes 15 the cam 27 to shift the pivotal support 23 in the slot 25 by means of the link 29 an amount which is proportional to the thickness of the material between the presser-foot 13^a and the feed-dog 15. This causes the 20 take-up eye 14^a to move downwardly below the thread guide 17 so as to take up and advance an amount of thread proportional to the thickness of the material so that the requisite amount of thread is taken up to 25 form the succeeding stitch and to form a thread loop large enough to be passed around the bobbin case by the loop-taker. The 30 presser-foot 13^a is raised or lowered by an increase or decrease in the thickness of the 35 material which correspondingly increases or decreases the amount of thread taken up and advanced by the take-up lever 14, so that the machine operates effectively without 40 breaking or snarling the thread as the thickness of the material under the presser-foot varies during the sewing operation.

What I claim as new and desire to secure by Letters Patent of the United States, is:—

45 1. In a sewing machine, in combination, a presser-bar, means for taking up the thread in the machine during the stitch forming operation, and means for adjusting the length of thread taken up and advanced by 50 said take-up means, said adjusting means including a link, a slidably supported block attached thereto, and a cam on said presser-

bar for adjusting said block in response to variations in the thickness of the material 55 being sewn.

2. In a sewing machine take-up, in combination, means for guiding a thread, a lever including means for engaging the thread, a pivotal support for said lever, means for 60 oscillating said lever about said pivotal support, and means for adjusting said pivotal support relative to the means for oscillating said lever to vary the range of oscillatory movement of said lever and the length of the 65 thread taken up and advanced by the same in response to variations in the thickness of the material being sewn.

3. In a sewing machine, in combination, a presser-bar having a presser-foot thereon, 70 means for guiding a thread, a take-up including a lever having means for engaging the thread, a pivotal support for said lever, means for oscillating said lever about said pivotal support, and means actuated by said 75 presser-bar for adjusting said pivotal support relative to the means for oscillating said lever to vary the range of oscillatory movement of said lever and the length of the thread taken up and advanced by the 80 same in response to variations in the thickness of the material under said presser-foot.

4. In a sewing machine, in combination, a body member, a presser-bar supported on 85 said body member and having a presser-foot thereon, means for guiding a thread, a take-up including a lever having means for engaging the thread, a pivotal support for said lever, said body member having a guideway 90 slidably engaging said pivotal support, means for oscillating said lever about said pivotal support, and means actuated by said presser-bar for adjusting the position of said pivotal support in said guideway relative to 95 said body member to vary the range of the oscillatory movement of said lever and the length of the thread taken up and advanced thereby in response to variations in the thickness of the material under said presser- 100 foot.

In witness whereof, I have hereunto set my hand this 11th day of July, 1927.

HUGH M. STEPHENSON.
